Specification for Design.

Patented Sept. 6, 1921.

Application filed February 15, 1921. Serial No. 445,268. Term of patent 3½ years.

To all whom it may concern:

Be it known that I, REGINA TOBIZEL DRAGER, a citizen of the United States, residing at Seattle, in the county of King and State of Washington, have invented a new, original, and ornamental Design for Anklets, of which the following is a specification, reference being had to the accompanying drawing, forming part thereof, and in which—

Fig. 2 is a plan view of the anklet lying flat.

I claim:

The ornamental design for an anklet, as shown.

REGINA T. DRAGER.
